RAILWAY TRAFFIC CONTROLLING
APPARATUS

Henry S. Young, Wilkinsburg, Pa., assignor to The
Union Switch & Signal Company, Swissvale,
Pa., a corporation of Pennsylvania

Application August 27, 1941, Serial No. 408,483

9 Claims. (Cl. 246—26)

My invention relates to railway traffic controlling apparatus, and it has particular reference to the organization of such apparatus into novel and improved systems for controlling railway traffic from a remote control point. More particularly, my invention relates to remote control or centralized traffic control systems of the type wherein three-position control of the rear signal of two independently controllable signals governing traffic movements in the same direction over a stretch of track is governed by the advance signal in accordance with the polarity of current applied to a two-wire line circuit extending between such signals, and in which traffic locking for preventing conflicting traffic movements over the stretch is attained over the same two-wire line circuit.

An object of my invention is the provision, in a system of the above described class, of novel and improved means governed by the advance signal for controlling the polarity of current applied to a two-wire line circuit, whereby to effect control of the rear signal of a pair of successive signals governing traffic over a stretch of track.

Another object is the provision, in a system of the class described, of means whereby control established by an advance signal over the polarity of current supplied to a two-wire line circuit is made dependent upon the rear signal being conditioned for control over such line circuit.

A further object is the provision, in a signal system wherein signals governing traffic in opposite directions are controlled over circuits employing but two line wires, and in which the relative polarity of current applied to a line circuit at one end or the other may be reversed to provide three-position control of the signals for both directions, of novel and improved means for preventing reversal of current polarity at one end or the other of a line circuit in such manner as to connect two current sources to the line circuit in additive relation.

An additional object is the provision of novel and improved means for controlling the relative polarity of current supplied to the two-wire line circuit of a signal system of the class disclosed in United States Letters Patent No. 1,650,575, granted on November 22, 1927, to Herbert A. Wallace.

The above-mentioned and other important objects and characteristic features of my invention which will become readily apparent from the following description, are attained in accord-

ance with my invention by providing a system of the class described and having a two-wire line circuit provided with a source of current adjacent the advance signal for controlling the rear signal in accordance with the polarity of current supplied from the source to the circuit, with means governed by the advance signal and rendered effective to control the polarity of current supplied to the line circuit when and only when the rear signal is conditioned for control over the line circuit.

I shall describe several forms of apparatus embodying my invention, and shall then point out the novel features thereof in claims.

15 In the accompanying drawings, Fig. 1 is a diagrammatic view illustrating one form of apparatus embodying my invention. Figs. 2, 3 and 4 are diagrammatic views each showing modifications of a portion of the apparatus shown in Fig. 1.

In each of the several views, similar reference characters have been employed to designate corresponding parts.

Referring to the drawings, the line diagram 25 at the top of Fig. 1 represents a stretch of railway track divided into a plurality of successive adjoining insulated track sections 1T, 2T and 3T. Each section of track is provided in the usual manner with a closed circuit track circuit including a normally energized track relay, designated by the reference character TR with a suitably distinguishing prefix, and the association of each track relay with its section is indicated conventionally by a dotted line extending from 30 the track relay to its associated section. A siding or passing track is connected to section 1T by a switch 1S, while another siding or passing track is connected to section 3T by a switch 3S. These switches S may be operated, preferably 35 by power, in any suitable manner by means not comprising a part of my present invention and hence not illustrated in the drawings.

The movement of eastbound traffic, operating over the stretch of track from left to right as viewed in the drawings, is governed by a pair of signals R2 and R4, while westbound traffic operating over the stretch is governed by a pair of signals L2 and L4. These signals are preferably capable of displaying three aspects, and may be 45 of any suitable type such as searchlight, position light, color light, etc. For the purposes of the present description, I shall assume that the signals R and L are searchlight type signals, each of which is provided with a circuit controller which 50 comprises one or more movable contact members

and a plurality of cooperating stationary contact members. For example, signal L2 has associated therewith a circuit controller comprising movable contact members 6 and 7 operatively associated with the mechanism of the signal, and stationary contact members 8, 9, 10 and 11. Contact member 6 of the controller is operated by the signal mechanism and engages contact member 8 or 9 according as the signal displays its caution indication or either its clear or stop indication. The other contact member 7 is operated by the signal mechanism and engages contact member 10 or 11 according as the signal displays its clear or either its caution or stop indication.

In order to simplify the drawings and to assist in tracing circuits, the circuit controllers associated with signals L2 and L4 have been represented in the drawings at points remote from the location of the associated signals, and the association of a controller with a signal is indicated by placing above the controller the reference character of the associated signal. Also, contacts have been represented in the drawings disposed remote from the relays operating such contacts, but in each of such cases the relay operating the contact has been indicated by placing above such contact the reference character of its associated relay.

Signals R2 and L2, which govern opposing traffic movements through section 1T, are controlled from a remote office station through the medium of field station apparatus preferably disposed adjacent section 1T and comprising two remote or code controlled stick relays one for each signal and each designated by the reference character HSR with a prefix corresponding to the reference character of its associated signal. The system for controlling the HSR relays from a remote office station may be a direct wire system using a line wire for each relay, or may be a code system in which all of the relays are controlled over a single circuit. I shall assume that the remote control or centralized traffic control system employed is of the time code type shown in United States Letters Patent No. 2,229,-249, granted on January 21, 1941, to L. V. Lewis. In such a system, a line code storage unit, designated by the reference character LCS, is provided for each field station and comprises apparatus selectively operated in response to code signals sent from the central office station. When a storage unit is operated, energy is made to appear at a terminal 12, 13 or 14, according to the code signal operating the unit. Energy is applied to terminal 12 or 13 of the operated unit only during the reception of the code signal to pick up the selected HSR relay. Energy remains on terminal 14 of the operated unit subsequent to the sending of the code signal to hold the selected HSR relay energized over a stick circuit.

Signals R4 and L4, which govern opposing traffic movements over section 3T, are likewise controlled from the remote office station through the medium of field station apparatus preferably disposed adjacent section 3T and comprising a line code storage unit LCS and stick relays R4HSR and L4HSR. Relay R4HSR or L4HSR is picked up according as positive energy is applied to terminal 12 or 13, respectively, and such relay is held up over its stick circuit made effective when energy is applied to terminal 14.

The signals R2 and L4, which govern opposing traffic movements over section 2T intermediate

the two siding tracks, are additionally controlled by apparatus associated with the field station apparatus and incorporating traffic locking means arranged to prevent simultaneous clearing of both signals, thereby preventing conflicting traffic movements through the signaled stretch. These means comprise two traffic locking relays, one for each signal R2 and L4, and each designated by the reference character ZR with a prefix corresponding to the reference character of the associated signal. Each traffic locking relay ZR has a back contact interposed in the pick-up circuit of the code controlled HSR relay of the associated signal, hence relay R2HSR for example may be picked up by the communication system when and only when relay R2ZR is released to close its back contact 15, and relay L4HSR may be picked up over the communication system only when relay L4ZR is released.

The traffic locking relays ZR are controlled by a two-wire line circuit extending from the field station apparatus adjacent section 1T to the field station apparatus adjacent section 3T. Each end of such circuit has associated therewith a suitable source of current such as a battery designated by the reference character SB with a suitably distinguishing prefix, and each end of such circuit also has associated therewith pole changing means, hereinafter referred to, for controlling the polarity of current supplied by the adjacent source of current to the line circuit. Each end of the line circuit also has associated therewith switching means, to be referred to hereinafter, for either connecting the two-wire line circuit to the adjacent source of current or conditioning such circuit to effect control of the adjacent one of the two signals R2 and L4.

The switching means may comprise as shown in Fig. 1, slow release repeater relays one for each signal control relay R2HSR and L4HSR, and which repeater relays are designated by the reference character F with a prefix corresponding to the prefix employed in the reference character of the associated HSR relay. Repeater relay L4F is controlled, for example, over a circuit extending from one terminal B of a suitable source of current, such as a battery not shown but having its opposite terminals designated by the reference characters B and C, through front contact 16 of its associated relay L4HSR, the winding of relay L4F, and back contact 17 of traffic locking relay L4ZR to the other terminal C of the source of current. Relay L4F has connected across its terminal an obvious shunt circuit path completed when back contact 16 of relay L4HSR is closed, whereby relay L4F may be made slow to release. The other relay R2F is similarly controlled by relay R2HSR, as is readily apparent from an inspection of the drawings.

As shown in Fig. 1, the signals R2 and L4 are arranged to be controlled by signal control relays R2HD and L4HD, respectively, which relays are normally disconnected from the two-wire line circuit. One signal control relay HD or the other is at times connected to the line circuit, to condition its associated signal for control over such circuit, at such times as the switching or repeating relay F of the associated stick relay HSR associated with signal R2 or L4 is picked up. These relays HD are preferably of the slow pick-up, retained neutral type of polarized relay which incorporates means, such as

hold-down pole pieces, arranged to delay the pick-up of the neutral armature of the relay.

The manner in which a relay HD controls its associated signal is not represented in the drawings since such control may take any one of many forms well-known in the art. For the purposes of this description, therefore, it is deemed sufficient to state that when a relay HD is de-energized, its associated signal is caused to display its stop indication; when relay HD is energized by current of one relative or normal polarity, its associated signal is caused to display an approach indication; and when a relay HD is energized by current of the other or reverse polarity, the associated signal is caused to display its clear indication.

The pole changing means, hereinbefore referred to, comprise relays designated by the reference character PCR with suitably distinguishing suffixes, and arranged in a manner to be made clear hereinafter, to become energized only after the adjacent traffic locking relay ZR is picked up.

The apparatus embodying my invention is in its normal condition, as represented in Fig. 1, when all code controlled relays HSR are released and the signaled stretch of track is unoccupied. In this condition of the apparatus, eastbound signals R2 and R4 and westbound signals L2 and L4 display their respective stop aspects; and the track relays TR are all picked up. The switching relays F and the pole changing relays PCR are deenergized, and the sources of current at the ends of the two-wire line circuit are connected in series opposition over a circuit which may be traced from one terminal of battery 1SB, through asymmetrical unit 21 in its low resistance direction, the winding of relay R2ZR, back contact 22 of relay L2PCR, back contact 23 of relay R2F, front contacts 24, 25 and 26 of relays 1TR, 2TR and 3TR, respectively, back contact 27 of relay L4F, back contact 28 of relay R4PCR, the winding of relay L4ZR, asymmetrical unit 29 in its high resistance direction, the one terminal of battery SB, through the battery to the other terminal of battery 2SB, back contact 30 of relay R4PCR, back contact 31 of relay L4F, front contacts 32, 33 and 34 of relays 3TR, 2TR and 1TR, respectively, back contact 35 of relay R2F, back contact 36 of relay L2PCR, and to the other terminal of battery 1SB. Relays R2ZR and L4ZR are deenergized since with the batteries 1SB and 2SB connected in opposition, substantially no current flows in the line circuit. Also, the asymmetrical units 21 and 29, interposed in the line circuit, function to prevent a current flow and hence energization of either traffic locking relay ZR should the electromotive forces of the two batteries become unbalanced when such batteries are connected in series opposition.

If, now, the operator wishes to authorize a westbound movement over the stretch, he will under normal conditions, first control the communication system to cause relay L4HSR to pick up, thus causing repeater relay L4F to become energized over its circuit previously traced and including front contact 16 of relay L4HSR and back contact 17 of relay L4ZR. The energization of relay L4F causes its back contacts 27 and 31 to open to disconnect relay L4ZR and battery 2SB from the line circuit, and front contacts 27 and 31 of relay L4F close to connect relay L4HD to the line circuit and thus condition signal L4 for control over such circuit, which circuit now includes front contact 38 of relay L4HSR and the winding

of relay L4HD. I shall assume that the current supplied from battery 1SB to the line circuit when pole changing relay L2PCR is released, is of the one relative polarity and causes relay L4HD to be energized in the direction to cause its associated signal L4 to display its approach indication. Relay R2ZR is at this time energized and opens its back contact 15, thereby opening the pick-up circuit of relay R2HSR to prevent energization of such relay over the communication system. It follows, therefore, that with relay L4HSR energized to control signal L4 to permit a westbound movement, the opposing signal R2 cannot be controlled by the operator over the communication system, and hence conflicting traffic movements are prevented.

After having established control over westbound signal L4, the operator will then clear westbound signal L2 by suitably controlling the communication system to pick up relay L2HSR, whereupon signal L2 is caused to display either its caution or its proceed indication in accordance with traffic conditions in advance. Pole changing relay L2PCR associated with signal L2 accordingly becomes energized over a circuit extending from terminal B through either contact 7-10, or contact 7-11 and contact 6-8, of the circuit controller associated with signal L2, the winding of relay L2PCR, and front contact 17 of relay R2ZR to terminal C. It is to be noted that the circuit of relay L2PCR is carried through front contact 17 of relay R2ZR, hence it follows that pole changing relay L2PCR may be picked up only if traffic locking relay R2ZR is picked up. Also, it is to be noted that a resistor 40 is connected across the terminals of relay L2PCR when front contact 17 of relay R2ZR is closed. The function of resistor 40 will be pointed out hereinafter.

The energization of relay L2PCR causes its front contacts 22 and 36 to close and pole change the current supplied from battery 1SB to the two-wire line circuit, thereby causing the current supplied to relay L4HD to have a polarity such as to cause the relay to swing its polar contact members to their other positions to cause signal L4 to display its clear indication. The rear signal L4 is, therefore, controlled by the advance signal in accordance with the polarity of current supplied over the two-wire line circuit.

At this time, it should be noted that the apparatus embodying my invention is so arranged as to prevent a "locked-up" condition if the operator authorizes a westbound movement by first clearing signal L2. For example, if the apparatus of Fig. 1 is in its normal condition as represented in the drawing, and the operator clears signal L2 by causing the communication system to pick up relay L2HSR, this operation has at this time no effect on the two-wire line circuit. Pole changing relay L2PCR, for example, does not pick up since traffic locking relay R2ZR is released and front contact 17 is opened, hence back contacts 22 and 36 of relay L2PCR remain closed and batteries 1SB and 2SB are not connected in additive relation, as would happen if the pole changing means of the circuit were operated by and directly repeated the position of signal L2. It follows, therefore, that the arrangement is such as to avoid improper energization of both advance traffic locking relays R2ZR and L4ZR, caused by the additive relation of both batteries of the two-wire line circuit, when the advance signal L2 is cleared prior to clearing rear signal L4.

Under the conditions assumed, that is, with

signal L2 cleared, the operator may clear signal L4 by causing the communication system to pick up relay L4HSR, thereby causing switching relay L4F to pick up and connect control relay L4HD to the line circuit to condition signal L4 for control over such circuit. When this happens, relay R2ZR of course picks up since battery 1SB is no longer opposed by battery 2SB, and front contact 17 of relay R2ZR closes to complete the circuit of pole changing relay L2PCR, whereupon that relay picks up to close its front contacts 22 and 36 to cause the current supplied from battery 1SB to the line circuit to have the polarity such as to cause relay L4HD to swing its polar contact members to their positions wherein signal L4 is caused to display its proceed indication. The slow pick-up characteristics of the retained neutral polarized relay L4HD are selected to be such that relay L4HD does not pick up its neutral armature until after relay L2PCR picks up to pole change the current supplied to the line circuit, thereby to avoid a transitory display of the caution indication of signal L4, such as would occur if relay L4HD immediately picked up when first connected to the line circuit when relay L2PCR is released to cause current of the one polarity to be supplied to the line circuit. It follows, therefore, that under the conditions assumed, signal L4 will be caused to operate from its stop directly to its clear position and a transitory display of the caution indication is prevented.

Signal L4 is, of course, caused to display its stop aspect when the train enters the stretch and shunts any one or more of the track relays 1TR, 2TR or 3TR to cause the two-wire line circuit to become opened. After the westbound train vacates the stretch, signal L4 is first caused to display its caution indication, due to signal L2 being controlled to its stop position in accordance with the usual practice by apparatus not shown in the drawings, and then after signal L2 is caused to display either its caution or its clear indication, signal L4 is caused to display its clear indication.

The signals may be manually set to stop by the operator suitably controlling the communication system to cause the release of relays L2HSR and L4HSR. Ordinarily, the operator will first set signal L2 to stop, whereupon the circuit controller operated by signal L2 assumes its normal position to deenergize pole changing relay L2PCR, which relay at this time has resistor 40 connected in multiple with its winding, hence the relay is made slightly slow to release. At the end of its slow release interval, relay L2PCR releases to close its back contacts 22 and 36 to cause battery 1SB to apply current of normal polarity to the two-wire line circuit.

Signal L4 ordinarily is controlled by the operator to its stop position immediately after signal L2 is set to stop, and the slow release interval of relay L2PCR is preferably selected so as to maintain such relay picked up until relay L4HSR is released over the communication system, thus causing front contact 38 of relay L4HSR interposed in the two-wire line circuit, to open and thus open that circuit and cause the release of relay L4HD. Front contact 16 of relay L4HSR also opens to open the circuit of switching relay L4F. Relay L2PCR is adjusted to release prior to the release of relay L4F which latter relay is made slow to release, in part due to the shunt circuit path connected across its terminals through back contact 16 of relay L4HSR, hence

it follows that when signals L2 and L4 are sequentially set to stop by the operator, the rear signal is caused to operate directly from its clear position to its stop position without causing a transitory display of its caution indication; and that when switching relay L4F releases, the batteries 1SB and 2SB are connected in their normal opposed relation.

In the event that signal L4 is manually put to stop prior to signal L2 being put to stop, by the operator suitably controlling the communication system to release relay L4HSR, front contact 38 of relay L4HSR opens to open the two-wire line circuit, thereby deenergizing relays L4HD and R2ZR. Relay R2ZR thereupon releases, and opens its front contact 17 to deenergize pole changing relay L2PCR, which relay releases immediately, since with front contact 17 of relay R2ZR open, resistor 40 is not connected across relay L2PCR to delay its release, and back contacts 22 and 36 of relay L2PCR close to cause battery 1SB to supply current of normal polarity to the line circuit. Slow release relay L4F, which becomes deenergized when front contact 16 of relay L4HSR opens, is proportioned to remain picked up until after relay L2PCR releases, hence when relay L4F releases, the two-wire line circuit is restored to its normal condition as represented in the drawings, and in which condition batteries 1SB and 2SB are connected in series opposition. Signal L2 may, of course, be set to stop when the operator causes the communication system to release relay L2HSR.

With the apparatus in its normal condition, as shown in the drawings, the operator may authorize an eastbound movement by suitably controlling the communication system to cause relays R2HSR and R4HSR to pick up. The apparatus operates in such event to clear signals R2 and R4, in a manner believed to be obvious from an inspection of the drawings taken in connection with the foregoing detailed description of the operation of the apparatus for clearing the westbound signals L2 and L4, and further detailed explanation is deemed unnecessary.

Figs. 2, 3 and 4, each show modifications of the signal control portion of the two-wire line circuit represented in Fig. 1. In Fig. 2, operating windings 50 of the signal mechanisms are illustrated as being energized directly from the two-wire line circuit, and the slow pick-up retained neutral polarized relays HE, employed in Fig. 1, are dispensed with. The apparatus, modified as shown in Fig. 2, operates in a manner believed to be obvious from an inspection of the drawing, it being noted however, that the apparatus of Fig. 2 might cause the rear signal, such as signal L4, to display a transitory caution indication if signal L2 is cleared prior to signal L4. This transitory caution indication results from the fact that pole changing relay L2PCR is picked up only after signal L4 is conditioned for control over the line circuit, hence after signal L4 is connected by relay L4F to the line circuit, current of normal polarity is first supplied to the line circuit over back contacts 22 and 36 of relay L2PCR during the pick-up interval of relays R2ZR and L2PCR. This current of normal polarity might cause signal L4 to display its caution indication. Then, after relay L2PCR picks up, current of the other polarity is supplied to the line circuit and will cause signal L4 to display its clear aspect.

In Fig. 3, the slow release repeater relays R2F and L4F, employed in Figs. 1 and 2, are dispensed with. The switching means for the two-wire line

circuit now comprise contacts operated by the remote or code controlled relays HSR associated with the rear signals R2 and L4, and each of these code controlled relays is provided with a slow pick-up repeater relay, designated by the reference character GR with a prefix corresponding to the prefix employed in the reference character of the associated code controlled HSR relay. Each repeater relay GR controls the energization of the operating winding 50 of the associated signal operating mechanism by connecting such winding to or disconnecting it from the two-wire line circuit. For example, relay L4GR is normally deenergized and its back contact 52 is closed to condition the two-wire line circuit initially to be completed through a resistor 51 when front contacts 53 and 54 of relay L4HSR close. At the end of its slow pick-up interval, relay L4GR picks up to open its back and close its front contact 52, thereby connecting operating winding 50 to the two-wire line circuit. The slow pick-up characteristics of the repeater relays GR are selected to bridge the pick-up intervals of the traffic locking relays ZR and pole changing relays PCR, thereby to prevent a transitory display of the caution indication by the rear signal if the advance signal is first to clear. When an advance signal is cleared, as when signal L2 is cleared, and the rear signal L4 is subsequently controlled by the operator to its clear condition, relay R2ZR is picked up when code controlled relay L4HSR picks up, and relay L2PCR accordingly picks up to reverse the polarity of energy supplied to the line circuit prior to repeater relay L4GR picking up to connect the line circuit to operating winding 50 of the mechanism of signal L4. It follows, therefore, that when relay L4GR picks up, the current polarity in the line circuit is such as to cause signal L4 to operate directly to its clear position.

In Fig. 4, thermal time element relays TER and signal repeater relays RGPR are provided and are arranged to prevent a transitory display of the caution indication when an advance signal is cleared prior to its associated rear signal being cleared. Each rear signal R2 and L4 controls its associated repeater relay RGPR over an obvious circuit shown in Fig. 4 and completed when the signal is in its stop position. Each time element relay TER is provided with an energizing circuit controlled by the adjacent repeater relay RGPR and the code controlled relay associated with the associated signal. For example, relay L4TER is provided with a circuit extending from terminal B through front contact 56 of relay L4HSR, front contact 57 of relay L4RGPR, and the thermal unit of relay L4TER to terminal C.

The repeater relays RGPR and time element relays TER of Fig. 4 cooperate in controlling a shunt path connected across operating winding 50 of the associated rear signal R2 or L4, and thereby delays the energization of such operating winding in a manner substantially corresponding to the manner that repeater relays GR in Fig. 3 delay the energization of the operating windings 50 of the signal mechanisms of Fig. 3. For example, in Fig. 4, repeater relay L4RGPR is normally energized while thermal relay L4TER is deenergized. A circuit path, connected through front contact 59 of relay L4RGPR and normally closed thermal contact 58 of the thermal relay L4TER, is therefore connected in multiple with operating winding 50 of the signal mechanism of signal L4. It follows that when signal control relay L4HSR is picked up after relay L2HSR is picked up, and

front contacts 53 and 54 of relay L4HSR close to connect winding 50 in circuit with the two-wire line circuit, the shunt path across winding 50 is opened only at the end of the interval required for relay L4TER to open its thermal contact 58. This interval is selected to bridge the pick-up intervals of relays R2ZR and L2PCR, shown in Fig. 1, and it follows that when thermal contact 58 opens to open the shunt path on winding 50 of the signal mechanism of signal L4, the current supplied to such winding is of the proper polarity to cause the signal to operate directly to its clear position. When this happens, repeater relay L4RGPR releases to open its front contact 57, thereby opening the energizing circuit of thermal relay L4TER. Front contact 59 of relay L4RGPR also opens so that when thermal contact 58 of relay L4TER again closes, the shunt path around winding 50 of signal L4 is maintained open.

Although I have herein shown and described only a few forms of railway traffic controlling apparatus embodying my invention, it is understood that various changes and modifications may be made therein within the scope of the appended claims without departing from the spirit and scope of my invention.

Having thus described my invention, what I claim is:

1. In combination, a stretch of railway track, two successive signals governing traffic in the same direction through said stretch, a two-wire line circuit having a source of current adjacent the advance signal for controlling the rear signal in accordance with the polarity of current applied by said source to said line circuit, independently operable control means for each signal, means governed by the control means associated with said rear signal for conditioning said signal for control over said line circuit, means governed by the control means associated with said advance signal for controlling the polarity of current applied from said source to said line circuit, and means associated with said line circuit adjacent said advance signal for rendering ineffective said last-mentioned means unless said rear signal is conditioned for control over said line circuit.

2. In combination, a stretch of railway track, two successive signals governing traffic in the same direction through said stretch, a two-wire line circuit extending between said signals for controlling the rear signal in accordance with the polarity of current supplied to said circuit, independently operable control means for each signal, means governed by the control means associated with said rear signal for conditioning said rear signal for control over said line circuit, a source of current, means governed by said advance signal for controlling the polarity of current supplied from said source to said circuit, and means associated with said line circuit at said advance signal for preventing control by said advance signal of said current polarity until said rear signal is conditioned for control over said line circuit.

3. In a railway signal system for a stretch of railway track provided with two successive signals governing traffic in the same direction through the stretch, said signal system comprising independently operable control means for each signal, a two-wire line circuit having a source of current adjacent the advance signal for controlling the rear signal in accordance with the polarity of current applied by said source to the

line circuit, and means governed by the control means of the rear signal for conditioning said rear signal for control over said line circuit, the combination in such a signal system of means interposed in said line circuit adjacent said source and operative when said rear signal is conditioned for control over said line circuit, and means governed by the control means of said advance signal for controlling the polarity of current applied by said source to said line circuit when and only when said last-mentioned means is operative.

4. In combination, a stretch of railway track provided with a pair of successive signals governing traffic in one direction and another pair of successive signals governing traffic in the opposite direction through said stretch, independently operable control means for controlling each of said signals, a line circuit for controlling the rear signal of each of said pairs in accordance with the polarity of current applied to said circuit, two sources of current one at each end of said line circuit and two locking relays one associated with each source, means governed by the control means associated with each of said rear signals for at times conditioning such signal for control over said line circuit and at other times for connecting the adjacent source and locking relay to said line circuit, whereby to energize a locking relay by current from its associated source only when the rear signal at the opposite end of the line circuit is conditioned for control over said circuit, and means governed by the advance signal of each pair for controlling the polarity of current supplied to said circuit when the locking relay at the adjacent end of the line circuit is energized.

5. A railway signal system, provided for a stretch of railway track having an advance and a rear signal for governing traffic in the same direction through said stretch; said signal system comprising independently operable control means for each signal, two sources of current one for each signal and a locking relay for the advance signal, a line circuit for normally connecting said locking relay and two sources in a series circuit with said sources connected in opposition, whereby said locking relay is normally released, means governed by the control means of said rear signal for at times disconnecting the associated source from said line circuit and for conditioning said rear signal for control over said line circuit in accordance with the polarity of current supplied from the other source through said locking relay to said line circuit, and pole changing means associated with the advance signal and controlling the polarity of current supplied from the said other source to the said line circuit to cause said current to have one relative polarity or the other; said system being characterized by the fact that said pole changing means comprises a relay energized over a circuit including a front contact of said locking relay and a contact closed only when said advance signal is cleared.

6. A railway signal system provided for a stretch of railway track having a pair of successive signals governing traffic in one direction and another pair of signals governing traffic in the opposite direction through said stretch, said signal system comprising; independently operable control means for controlling each of said signals, two sources of current and two locking relays, one of each for the advance signal of each pair of signals, a line circuit for normally connecting said two locking relays and said two

sources in a series circuit with said sources connected in opposing relation, whereby said two locking relays are normally released, means governed by the control means of each rear signal for at times disconnecting the adjacent source and locking relay from said circuit and for conditioning such rear signal for control over said circuit, whereby to energize a locking relay by current from its associated source only when the rear signal at the opposite end of said circuit is conditioned for control over said circuit, and pole changing means governed by the advance signal of each pair for at times controlling the polarity of current supplied to said circuit from its adjacent source; said system being characterized by the fact that the pole changing means associated with each advance signal comprises a relay energized over a circuit including in series a contact of the associated advance signal closed only when said signal is cleared and a front contact of the locking relay associated with such signal.

7. A railway signal system provided for a stretch of railway track having a pair of successive signals governing traffic in one direction and another pair of successive signals governing traffic in the opposite direction through said stretch, said signal system comprising; independently operable control means for controlling each of said signals, two sources of current and two locking relays, one of each for the advance signal of each pair of signals, two slow pick-up retained neutral polarized control relays one for each of the rear signals, a line circuit for normally connecting said two locking relays and said two sources in a series circuit with said sources connected in opposing relation, whereby said two locking relays are normally released, means governed by the control means of each rear signal for at times disconnecting the adjacent source and locking relay from said circuit and for connecting to such circuit the control relay of such rear signal, whereby to energize a locking relay by current from its associated source only when the control relay of the rear signal at the opposite end of said circuit is connected to said circuit, and pole changing means governed by the advance signal of each pair for at times controlling the polarity of current supplied to said circuit from its adjacent source; said system being characterized by the fact that the pole changing means associated with each advance signal comprises a relay energized over a circuit including in series a contact of the associated advance signal closed only when said signal is cleared and a front contact of the locking relay associated with such signal.

8. A railway signal system provided for a stretch of railway track having a pair of successive signals governing traffic in one direction and another pair of successive signals governing traffic in the opposite direction through said stretch, said signal system comprising; independently operable control means for controlling each of said signals, two sources of current and two locking relays, one of each for the advance signal of each pair of signals, a line circuit for normally connecting said two locking relays and said two sources in a series circuit with said sources connected in opposing relation, whereby said two locking relays are normally released, means governed by the control means of each rear signal for at times disconnecting the adjacent source and locking relay from said circuit and for connecting to such circuit the operating

element of such rear signal, whereby to energize a locking relay by current from its associated source only when the operating element of the rear signal at the opposite end of said circuit is connected to said circuit, and pole changing means governed by the advance signal of each pair for at times controlling the polarity of current supplied to said circuit from its adjacent source; said system being characterized by the fact that the pole changing means associated with each advance signal comprises a relay energized over a circuit including in series a contact of the associated advance signal closed only

5 when said signal is cleared and a front contact of the locking relay associated with such signal, and being further characterized by the provision of means effective when a rear signal operating mechanism is connected to the line circuit, to initially shunt such mechanism for a predetermined time interval.

10 9. The signal system of claim 8 characterized by the fact that two time element relays, one for each rear signal, are provided, each for shunting the operating mechanism of its associated signal for said predetermined time interval.

HENRY S. YOUNG.
